HENRY D. ROACH, OF MINNEAPOLIS, MINNESOTA

AUTOMATIC SASH OPERATOR

Application filed January 17, 1930. Serial No. 421,429.

This invention relates to automatic sash operators.

It is an object of this invention to provide a novel and improved storm sash operator of cheap and simple construction which will automatically open and close a swinging storm sash applied to a window frame as a sliding window sash mounted in the frame is raised and lowered.

10 It is another object of the present invention to provide such an operator for the storm sash which has no positive connection with the window sash and will permit the window sash to be raised to its full height.

15 To these ends, the invention consists in the novel parts and novel combinations of parts, hereinafter defined in the claims and described in the following specification, made in connection with the accompanying 20 drawings, wherein like reference characters refer to the same or similar parts throughout the various views and, in which,

Fig. 1 is a vertical section through a window frame having mounted therein a sliding window sash and a swinging storm sash, the same frame being equipped with an embodiment of the present invention and the parts being shown in one position in full lines and in another position in dotted lines;

30 and

Fig. 2 is a horizontal section taken on the line 2—2 of Fig. 1.

Referring to the drawings, portions of a window frame of standard construction are 35 illustrated, which include the jamb 3, sill 4, window board 5, inner abutment strip 6 for the lower window sash, spacing strip 7 between the lower window sash and the upper window sash and spacing strip 8 between the upper window sash and the storm sash. The lower window sash mounted for vertical sliding movement is designated by the numeral 9 and carries the pane of glass 10. The storm sash is designated by the numeral

40 11 and carries the pane of glass 12. The storm sash 11 is pivoted at its upper end (not illustrated) for swinging movement of the lower end of the sash outwardly from the window frame.

45 In accordance with the present invention,

a bell crank lever 13 is provided which is pivoted at its fulcrum portion between the two sashes 9 and 11 to the window frame by means of a pivot 14 which may comprise merely a screw secured to the outer spacing 55 strip 8. The bell crank lever 13 has an arm 13a which normally projects upwardly from the pivot 14 when the two sashes 9 and 11 are closed and may, accordingly, be called the upper arm of the lever. The bell crank 60 lever 13 also has an arm 13b which normally projects downwardly and inwardly from the pivot 14 when the sashes 9 and 11 are closed and, accordingly, may be designated the lower arm of the lever. Pivoted securely to the end of the upper arm 13a is a U-shaped slider 15 through which a rod 16, fixed to the lower portion of one side of the storm sash 11, extends. The rod 16 forms a track to permit sliding movement of slider 70 15 upwardly and downwardly thereon and for this reason the rod 16 is preferably inwardly spaced at its medial portion from the storm sash 11, the two ends of the rod being preferably bent as shown and flattened in order that they may be readily secured to the storm sash. The lower end of the rod 16 will act as a stop to limit the downward movement of the slider 15 and, accordingly, the upward movement of the 75 arm 13b of the lever. The end of the lower arm 13b is screwthreaded and has secured thereto a screwthreaded socket 17 provided at its lower end with a forked portion through which a pivot 18 extends carrying a roller 19. At diametrically opposite points on the inner end of the socket 17, apertured ears 17a are formed and a coiled tension spring 20 is hooked at one end through the aperture in one of the ears 17a and is secured at its other end to an eye 21 mounted on the jamb 3 between the strips 7 and 8 well above the pivot 14.

In installing one of the operators on a window frame, before the spring 20 is attached to the socket 17, the socket will be screwed inwardly or outwardly on the screwthreaded portion of the arm 13b of the bell crank lever, until when the lower window sash 9 and the storm sash 11 are both closed,

the roller 19 will strike and tightly abut the outer side of the lower portion of the window sash 9. The spring 20 may be then hooked through the aperture in one of the 5 ears 17a, two ears preferably being provided so that quite fine adjustment of the spacing of the roller 19 from the pivot 14 may be provided. The spring 20 when attached, will then hold the socket 17 from 10 turning relative to the lower arm 13b and will maintain the pivot 18 for the roller 19 in horizontal position.

Considering that the two sashes 9 and 11 are in the closed position illustrated in Fig. 15 1, the parts of the sash operator will assume the position indicated in full lines Fig. 1, the spring 20 exerting tension on the arm 13b to urge the same upwardly. When the window sash 9 is raised, the window sash 20 will be moved relative to the bell crank lever until the outer edge of the window sash is carried upwardly past the roller 19, the roller acting to permit this movement without undue friction. When the lower edge 25 of the window sash is raised above the lower position of the roller as shown in full lines Fig. 1, the spring 20 will cause the arm 13b of the bell crank lever to be carried upwardly with the window sash below the 30 same until the lower arm 13b has arrived at the position indicated in dotted lines Fig. 1 with the roller 19 projecting directly into the path of downward movement of the window sash 9. During this movement of 35 the lower arm 13b, the upper arm 13a will be swung downwardly and outwardly causing the slider 15 to move downwardly on the rod 16 to swing the lower portion of the storm sash 11 outwardly to the dotted position and thereby opening the storm sash. 40 As has been stated, the lower portion of the rod 16 will limit the downward sliding movement of the slider 15 on the rod and this limiting action will occur to prevent further movement of the bell crank lever 13, while the roller 19 in its upward movement still projects in the path of downward movement of the window sash 9. The window sash can, of course, be raised to its full 45 height without affecting the operator after the window sash has been first raised to a point immediately above the dotted position of the roller 19 shown in Fig. 1. The distance that the storm sash 11 will be swung 50 open will, of course, depend on the extent that the window sash 9 is raised until the window sash is raised to such a point that it extends above the dotted position of the roller 19 in the drawings, whereupon the 55 storm sash will be swung open to its fullest possible extent. The draft of fresh air into the room may thus be varied at will depending on the height to which the window sash 9 is raised.

60 When the window sash 9 is lowered, after

having been raised, the lower edge of the sash will first strike the roller 19 and swing the lower arm 13b of the bell crank lever downwardly with the sash until the lower and outer edge of the sash is carried past the 70 roller. In this position, the parts of the operator and storm sash 11 will have been swung to the position shown in full lines Fig. 1, with the storm sash completely closed and abutting the strip 8. As the window 75 sash 9 is lowered beyond this point, the lower edge of the sash will be carried downwardly beyond the roller 19 and the roller will, accordingly, run upwardly a short distance on the outer side of the lower portion 80 of the window sash, so that the storm sash will be securely locked in closed position. In this position it will be impossible to open the storm sash from the outside of the house or other structure within which the window frame is situated and it will be unnecessary to lock the upper and lower sashes of the window together. As the storm sash will be tightly held in closed position, there will be no danger that the same will rattle or 90 will be caught by the wind and blown off the window frame.

In practice, two of the operators will preferably be provided for each window frame, one operator being situated at each side of 95 the frame. The operator can be readily removed with the storm sash from the window frame by merely unscrewing the screw 14 forming the pivot for the bell crank lever 13 and unhooking one end of the spring 20. 100 The operator can be similarly very easily installed when the storm sash is placed on the window frame for winter use. As the operators have no positive connection with the lower window sash 9, the window sash is 105 capable of its full natural sliding movement and the operators will not prevent raising movement of the sash 9 for cleaning of the pane 10 or the like.

The parts of the present device are few, 110 and the construction and operation of the same are simple. The device has been successfully demonstrated in actual practice.

It will, of course, be understood that various changes may be made in the form, details, arrangement and proportions of the various parts without departing from the scope of the present invention.

What is claimed is:—

1. The combination with a sash frame, a 120 sliding sash and a swinging sash mounted therein, of a bell crank lever pivoted between said sashes and having an upper arm normally extending above the pivot of the lever and a lower arm extending below the pivot of the lever, a sliding pivotal connection for securing the upper arm to the swinging sash, the lower arm being adapted to abut the lower portion of the sliding sash when the two sashes are closed and resilient means 125 130 135

urging said lower arm upwardly and into the path of said sliding sash.

2. The combination with a sash frame, a sliding sash and a swinging sash mounted therein, of a lever pivoted to the frame between said sashes, said lever having an upper arm normally extending above the pivot of the lever and a lower arm normally extending below the pivot of the lever, a slider pivoted to the upper arm, a track mounted on said swinging sash and upon which said slider is adapted to ride, said lower arm being adapted to abut said sliding sash when the two sashes are closed and resilient means urging said lower arm upwardly and into the path of said sliding sash.

3. The combination with a sash frame, a sliding sash and a swinging sash mounted therein, of a bell crank lever pivoted to said frame between said sashes, said lever having an upper arm normally extending above the pivot of the lever and a lower arm normally extending below the pivot of the lever, a sliding pivotal connection for securing the upper arm to said swinging sash, a roller mounted on the lower arm and adapted to abut the sliding sash when said sashes are closed and resilient means urging said lower arm upwardly to carry said roller into the downward path of said sliding sash when the sliding sash is raised.

4. A sash operator comprising a bell crank lever adapted to be pivoted to a sash frame between a sliding sash and a swinging sash, said lever having an upper arm and a lower arm, a track adapted to be secured to the lower portion of a swinging sash, a slider pivoted to the upper arm of said lever and mounted for sliding movement on said track, a roller mounted on said lower arm and a tension spring connected at one end to said lower arm and adapted to be connected at its other end to said sash frame.

5. The combination with a sash frame, a sliding sash and a swinging sash mounted therein, of a bell crank lever pivoted to the frame between said sashes, said lever having an upper arm normally projecting above its pivot and a lower arm normally projecting below its pivot, a socket mounted for longitudinal adjustment on said lower arm and adapted to abut said sliding sash when said sashes are closed, a sliding pivotal connection connecting said upper arm to said swinging sash and resilient means normally urging said lower arm upwardly.

6. The combination with a sash frame, a sliding sash and a swinging sash mounted therein, of a bell crank lever pivoted to the frame between said two sashes, said lever having an upper arm normally extending above the pivot for said lever and a lower arm normally extending below the pivot for said lever, a sliding pivotal connection connecting said upper arm to said

swinging sash, a socket carried at the lower end of said lower arm and adjustable longitudinally thereon, a roller carried by said socket and normally abutting the lower portion of said sliding sash when said two sashes are closed and a spring urging said lower arm upwardly.

7. The combination with a sash frame, a vertically slidable sash mounted therein and an outwardly swingable sash mounted therein, of an operator for said swinging sash adapted to swing the same outwardly as said sliding sash is raised, and to swing said swinging sash inwardly as said sliding sash is lowered, comprising a member pivoted between said two sashes and having sliding pivotal connection with said swinging sash at one end, said member at its other end being adapted to abut the lower portion of said sliding sash when said sashes are completely closed, means urging said last mentioned end of said member upwardly and said first mentioned end of said member outwardly and means permitting said last mentioned end of said member to be carried around the lower outer edge of said sliding sash, and into the downward path thereof, as the same is raised.

8. The combination with a window frame, a lower window sash slidably mounted therein and a swinging storm sash mounted therein for outward swinging movement, of a bell crank lever pivoted to the window frame between said sashes, said bell crank lever having an arm projecting upwardly from its pivot when said sashes are closed and having another arm projecting downwardly and inwardly from its pivot when said sashes are closed, a track mounted on said storm sash adjacent the lower portion thereof, a slider mounted on said track, said upper arm being pivoted to said slider, a socket mounted on to the end of said lower arm for longitudinal adjustment thereon, a roller mounted on said socket, said socket being adjusted on said arm so that when said two sashes are closed, said roller will abut the outer side of the lower portion of said window sash, a tension spring secured at one end to said socket and at its other end to said window frame and normally urging said lower arm upwardly whereby as said window sash is raised, said roller will be carried around the lower and outer edge of the window sash to a point below the window sash in the path thereof, and said spring will carry said lower arm upwardly for some little distance with the window sash as it is raised to swing the upper arm and the storm sash outwardly.

60 125 130

and cause said slider to move downwardly on said track, said track forming a stop to limit the upward swinging movement of said lower arm to such a position that said roller will remain in the path of said window sash.

dow sash as it is slid upwardly to its extreme upper position whereupon as the window sash is lowered, it will strike said roller to swing said lower arm downwardly and the upper arm and storm sash inwardly to carry the roller over the lower and outer edge of the window sash and against the outer side of the lower portion of the window sash to lock the storm sash in closed position.

In testimony whereof I affix my signature.

HENRY D. ROACH.
